United States Patent

Des. 238,395

Patented Jan. 6, 1976

238,395

DIAGNOSTIC TEST VIEWER

Eduardo V. Miranda and Lamont J. Seitz, Huntington Beach, Calif., assignors to Baxter Laboratories, Inc., Deerfield, Ill.

Filed Oct. 3, 1973, Ser. No. 402,952

Term of patent 14 years

Int. Cl. D10—04; D16—06
U.S. Cl. D57—1 E

FIG. 1.

FIG. 2.

FIG. 3.

FIG. 4.

FIG. 5.

FIG. 1 is a top perspective view of a diagnostic test viewer showing our new design;

FIG. 2 is a right side elevational view thereof;

FIG. 3 is a top plan view thereof;

FIG. 4 is a bottom plan view thereof; and

FIG. 5 is an elevational view taken from line 5—5 of FIG. 2.

We claim:

The ornamental design for a diagnostic test viewer, as shown and described.
